UNITED STATES PATENT OFFICE.

FRITZ STRIEGLER, OF FORT MCKAVETT, TEXAS.

AUTOMATIC TROUGH-VALVE.

1,347,353.

Specification of Letters Patent. Patented July 20, 1920.

Application filed May 21, 1918. Serial No. 235,787.

To all whom it may concern:

Be it known that I, FRITZ STRIEGLER, a citizen of the United States, residing at Fort McKavett, in the county of Menard 5 and State of Texas, have invented certain new and useful Improvements in Automatic Trough-Valves, of which the following is a specification.

This invention relates to new and useful 10 improvements in animal watering troughs and the primary object of the invention is to provide a new and useful improvement in an automatic float control valve for use in connection with the trough.

15 An object of the invention is to provide a controlling valve and mechanism therefor which will automatically maintain the water level in the watering trough, and which is adapted to prevent the water from overflowing therein should the controlling portion 20 of the mechanism break by automatically closing the inlet and preventing water from flowing into the trough.

Another object of the invention is to provide 25 a device of this character which is adapted for application to the conventional type of animal drinking trough, and which may be easily applied thereto with no change to the construction of the same.

30 A still further object of the invention is to provide a device of this character which is easily and simply constructed, inexpensive to manufacture, and one which will be very efficient in operation.

35 With these and numerous other objects in view, my invention consists of the novel features of construction, combination and arrangement of parts which will be herein referred to and more particularly pointed 40 out in the specification and claims.

In the accompanying drawings:

Figure 1 is a longitudinal sectional view through a portion of a watering trough, showing my improved valve controlling mechanism applied thereto,

Fig. 2 is a top plan view of the device.

In describing my invention, I shall refer to the drawings in which similar reference characters designate corresponding parts 50 throughout the several views. The numeral 1 designates a portion of the tank which is provided with a bottom 2 through which is mounted the inlet pipe 3 that projects up-

wardly through the bottom of the tank a short distance and has its upper end externally threaded.

55 Adapted to be positioned on the inlet pipe 3 within the tank 1 is an upstanding frame 4 which has its base portion 5 internally threaded, and adapted for co-operative engagement with the screw threaded upper end of the inlet pipe and said frame is provided with a pair of substantially U-shaped spaced arms 6 and 7 that extend upwardly therefrom at diametrically opposite points 60 on the base portion 5 and are connected at their upper ends as shown at 8. These arms are inverted and the construction thereof is clearly illustrated in Figs. 1 and 2 of the drawings. The base portion 5 of the frame 70 is provided with an inwardly extending annular flange 9 adjacent the lower edge thereof, which is adapted to seat on a gasket on the upper edge of the pipe 3 and which forms a valve seat 9', which operates in a 75 manner to be hereinafter more fully described.

The base portion of the frame 4 is provided with a guide 10 above the flange 9 and slidably mounted in said guide is a stem 80 11 of a valve 12 said valve being positioned within the upper end of the inlet pipe 3 and normally disposed on the valve seat 9'.

Pivottally mounted between one of the sides of the arms 6 and 7 of the frame 4, 85 is a normally horizontally disposed operating lever 13 which has a weight 14 on one end thereof while the other end is bent inwardly and then arcuately to form an arcuate rack 15 provided with a plurality of 90 spaced apertures therethrough. This last mentioned end of the lever 13 has pivotally connected therewith a rod 16 that is movable across the arcuate rack 15 and which has on its outer extremity a float 17 said float 95 having a plug 18 associated therewith so that oil or a similar substance lighter than water may be positioned therein.

The frame 4 has pivotally connected therewith on the side opposite from which the 100 lever 13 is mounted, a lever 19 which is horizontally disposed and extending across said frame and being connected by a link 20 with the lever 13. This lever 19 is likewise connected by a link 21 with the upper end of the 105 valve stem 11. By this construction, it is

obvious that upon movement downwardly of the arm of the lever 13 which carries the float 17 the said movement will be transmitted to the valve 12 through the stem 11 and hence forcing said valve downwardly, and opening the same to permit water to flow into the trough.

In Fig. 1 the tank has been shown as full and the float controlling mechanism in its position to close the valve 12. Should the water level lower in the tank 1 owing to the consumption of the same by the animals, the float 17 will become exposed and consequently increase in weight. The increase in weight of the float will overcome the action of the counterbalancing weight 14 which is always submerged and cause the lever 13 to rock, hence, forcing the valve stem 11 by its connection therewith downwardly to open the valve 12.

When the water level again reaches the point at which the float 17 is submerged the counterbalancing weight 14 begins to act, moving the lever 13 back to its normal horizontal position as clearly shown in Fig. 1. Attention is particularly directed to the fact that in the operation of this valve mechanism for controlling the flow of water, should the operating lever break or fail to work instead of the valve opening and permitting an uninterrupted flow of water into the trough the valve 12 will automatically close by the pressure of the water forcing the same in the seat 9', and hence any waste of water will be prevented. The float 17 is adjustable on the end of the operating lever 13 so that the depth of the water in the trough may be adjusted accordingly.

From the foregoing description taken in connection with the accompanying drawings it is thought that a clear and comprehensive understanding of the construction, operation and advantages of my invention may be had, and while I have shown and described the device as embodying a specific structure, I desire that it be understood that such changes may be made in said structure

as do not depart from the spirit and scope of the invention as claimed.

Having fully described my invention, what I claim is new, and desire to secure by Letters Patent, is:

1. The combination with a trough having an inlet pipe extending therein, of a valve normally seated by water pressure for regulating the inflow of water from the pipe, a horizontal operating lever connected with the valve, a submerged counter-balancing weight on one end of the lever, and a normally submerged float at the opposite end of the lever, the weight of the float when submerged being the same or slightly less than that of the counter-balance and greater than that of the counter-balance when resting on the surface of the water whereby to move the lever and unseat the valve when the surface of the water falls below said float.

2. The combination with a trough having an inlet pipe extending therein, of a valve normally seated by water pressure for regulating the inflow of water from the pipe, a horizontal operating lever connected with the valve and normally in a neutral position with respect thereto, a submerged counter-balancing weight on one end of the lever, a normally submerged float at the opposite end of the lever, the weight of the float when submerged being the same or slightly less than the counter-balance in order to maintain the lever in a non-operating position with respect to the valve and of a weight greater than the counter-balance when resting on the surface of the water whereby to move the lever and unseat the valve against the action of the counter balance when the surface of the water falls therebelow, and means for regulating the disposition of the float on the lever to increase or decrease the normal depth of the water in the tank.

In testimony whereof I affix my signature hereto.

FRITZ STRIEGLER.
